US0D1070922S

(12) **United States Design Patent** (10) Patent No.: **US D1,070,922 S**
(45) Date of Patent: ** Apr. 15, 2025

(54) **TURBINE SHROUD**

- (71) Applicant: **General Electric Company**, Schenectady, NY (US)
- (72) Inventors: **Sathyaranarayanan Raghavan**, Ballston Lake, NY (US); **Zachary John Snider**, Simpsonville, SC (US); **Changjie Sun**, Clifton Park, NY (US); **Gautam Suresh Naik**, Bangalore (IN); **Claire Fridtjof Lang**, Greenville, SC (US)
- (73) Assignee: **GE Infrastructure Technology LLC**, Greenville, SC (US)
- (**) Term: **15 Years**
- (21) Appl. No.: **29/741,077**
- (22) Filed: **Jul. 9, 2020**

(57) **CLAIM**

The ornamental design for a turbine shroud as shown and described.

DESCRIPTION

FIG. 1 is a perspective view of a first embodiment of a turbine shroud showing our new design.
FIG. 2 is a front view thereof.
FIG. 3 is a back view thereof.
FIG. 4 is a top view thereof.
FIG. 5 is a bottom view thereof.
FIG. 6 is a first side view thereof.
FIG. 7 is a perspective view of a second embodiment of a turbine shroud showing our new design.
FIG. 8 is a front view thereof.
FIG. 9 is a back view thereof.
FIG. 10 is a top view thereof.
FIG. 11 is a bottom view thereof; and,
FIG. 12 is a side view thereof.
The broken lines shown in the drawings are included for the purpose of illustrating portions of the turbine shroud that form no part of the claimed design.

1 Claim, 12 Drawing Sheets
